UNITED STATES PATENT OFFICE.

HAROLD M. HOWARD AND JAMES A. McHARDY, OF PROVIDENCE, RHODE ISLAND.

SPARK-PLUG.

1,158,222.

Specification of Letters Patent.

Patented Oct. 26, 1915

Application filed January 13, 1913. Serial No. 741,644.

To all whom it may concern:

Be it known that we, HAROLD M. HOWARD and JAMES A. McHARDY, citizens of the United States, and residents of the city of Providence, in the county of Providence and State of Rhode Island, have invented certain new and useful Improvements in Spark-Plugs, of which the following is a specification.

10 This invention relates to spark plugs, and has for its object to provide a plug of this character having a body shell completely closed at its inner end to prevent carbon or oil from getting into the shell and short circuiting the electrodes.

15 A further object of the invention is to support the central electrode in the insulating material, which closes the shell and to extend this electrode beyond the inner end 20 of the shell and to make the second electrode in the form of a loop to extend from one side of the shell to the other, around the end of said central electrode, whereby by supporting both ends of this second electrode it is 25 prevented from warping to better control the width of the sparking gap.

20 A further object of the invention is to form the inclosed insulating material in two parts, the inner part serving to close the corresponding portion of the shell and is itself held in position by the outer insulating portion, a packing being provided between the two portions to serve as a cushion and prevent breakage.

35 A still further object of the invention is to reduce the inner extremity of the central electrode where it passes through the end porcelain, so as to minimize the transmission of heat therethrough to the inner porcelain insulation to reduce the liability of breakage.

With these and other objects in view, the invention consists of certain novel features of construction, as will be more fully described and particularly pointed out in the appended claims.

45 Of the accompanying drawings: Figure 1— is a sectional elevation of my improved spark plug. Fig. 2— is an enlarged view showing the means for regulating the length of the central electrode to control the width of the sparking gap.

50 Referring to the drawings, 10 designates the outer end of the cylinder of an internal combustion engine to which our improved spark plug is shown as being attached. In

55 this plug 11 is the shell or casing which may be constructed of any suitable conducting material, such as iron, steel, brass, or the like, in a tubular form. The outer end of this shell at 12 is preferably made in hexagonal form to receive a wrench, and its inner end is threaded at 13 to be screwed into the cylinder. The inner surface at the outer end 14 of this shell is threaded to receive the 60 porcelain binding nut 15. The inner end of this shell is provided with an inwardly turned annular flange 16 forming a seat for the end closing member 17 which may be constructed of any suitable insulating material, such as porcelain or the like. The outer face of this seat portion is preferably flush with the corresponding end of the shell and its inner face is preferably made concave as at 18 for the purpose of receiving 65 the correspondingly shaped end 19 of the main insulating member 20. This main insulating member is for the purpose of carrying the central electrode 21, and its inner end is recessed at 22 for the reception of the 70 enlarged head 23 of said central electrode. The outer end of this electrode is threaded at 24 to receive the binding nut 25 and check nut 26, its opposite or gap forming end is reduced as at 27 to pass through a corresponding hole in the end member of the insulation. The protruding end of this electrode is threaded and provided with a thimble or sleeve 28 and a check nut 29, whereby the sleeve may be adjusted longitudinally 75 to regulate the gap across which the spark is to jump to the second electrode. This second electrode 30 is preferably formed of a wire of suitable material, bent into the form of a loop and having its ends driven or 80 forced into corresponding holes in the end of the shell to secure and support the same. One advantage of this construction is that by supporting both ends of this electrode its tendency to warp out of position is reduced 85 to the minimum, thereby preserving the required gap between the electrodes when in operation.

85 The shell of the ordinary spark plug is left vacant or open at its end and an excessive charge of carbon or oil soon fills up this chamber and short circuits the electrodes, rendering the spark plug inoperative until removed and cleaned. To obviate this difficulty we have completely closed the 90 shell by positioning the closing member 17 of the insulation at the inner end thereof

and have bound this seat member in position through a second insulating member 20 by means of the binding nut 15. When porcelain insulation is employed it is found of advantage to make the same in two parts as by so doing the breakage of the porcelain is reduced to the minimum. Then again, to again reduce the liability of breakage we have positioned a packing of yieldable material, such as asbestos or the like, between the two insulating members which serves a double purpose, first it prevents the two hard surfaces from contacting with each other again reducing the liability of breakage, and second, it serves to positively prevent any oil or carbon from working up through the central electrode hole thereby positively preventing short circuiting of the electrodes through the porcelain within the shell.

We claim:

1. A spark plug comprising an outer shell having an inturned lip adjacent its inner end, insulating material in said shell formed 25 of a relatively short inner member and a relatively long outer member, the inner member resting at its inner end against said

lip and comprising a block completely filling the corresponding portion of the shell, the outer end of the inner member being concaved and the inner end of the outer member being correspondingly convexed, a member 30 engaging said shell and clamping the outer insulating member against the inner member, and electrodes projecting from the inner end of the plug to form a spark gap.

2. A spark plug having a body portion closed at its inner end, an electrode projecting beyond the closed end, a grounded electrode formed of a looped wire and spaced 40 from the end of the projecting electrode to form a spark gap, said projecting electrode being provided with a thimble adjustable toward and from said looped wire to regulate the spark gap, and means for locking 45 said thimble in any adjusted position.

In testimony whereof we affix our signatures in presence of two witnesses.

HAROLD M. HOWARD.
JAMES A. McHARDY.
